UNITED STATES PATENT OFFICE.

FRANK MESKER AND THOMAS O. ARBEGUST, OF ST. LOUIS, MISSOURI,
ASSIGNORS TO MESKER & BROTHER, OF SAME PLACE.

WINDOW-FRAME.

SPECIFICATION forming part of Letters Patent No. 451,875, dated May 5, 1891.

Application filed May 3, 1890. Serial No. 350,529. (No model.)

To all whom it may concern:

Be it known that we, FRANK MESKER and THOMAS O. ARBEGUST, of St. Louis, Missouri, have jointly made a new and useful Improvement 5 in Window-Frame Construction, of which the following is a full, clear, and exact description.

The improvement relates to window-frames whose stiles are composed wholly or partly of sheet metal, and more especially to box window-frames and to building-fronts in which sheet metal is more or less employed; and it consists in the special mode of forming and uniting the parts immediately associated with the stiles of the window-frame, substantially as is hereinafter set forth and claimed, aided by the annexed drawing, making part of this specification, in which the improved construction is shown in horizontal section. The view 15 includes the window-frame and portions of the sides, respectively, of the window-frame of the adjoining columns. The top and bottom of the window-frame are not shown, the construction thereof being familiar.

20 A B represent the window-sashes.

C C' represent the stiles; D D', the inside-finish boards; E E', the inside-finish stops; F F', the studs; and G G, the weights.

In the present instance the studs F F' do 25 not extend outward as far as does the front face c of the stile, and the stile-face c, before it reaches a point in front of the stud, is turned inward at c' until in line, or thereabout, with the outer face f of the stud, and then the

metal sheet of which the stile is composed is 35 turned toward the stud, as shown at c² substantially, and the stile is united with the stud by having its flange c² nailed to a strip H, which in turn is nailed to the front face f of the stud. The strip is wider than the face 40 f of the stud and the side i of the sheet-metal column I is by means of nails i' secured to the side h of the strip H—that is, the side i of the column comes between the strip H and the part c' of the stile, all substantially as 45 shown.

We claim—

1. The combination of the sheet-metal stile, the stud, and the strip H, extending laterally beyond the outer face of said stud, and said 50 stile having one face adapted to stand in alignment with the outer face of said strip and to lap the inner or rear side of the latter, substantially as described.

2. The combination of the sheet-metal stile, 55 the sheet-metal column, the stud, and the strip extending laterally beyond the outer face of said stud, said stile having one face adapted to stand in alignment with the outer face of said strip and to lap the inner or rear 60 side of the latter, and said column having one edge secured between said strip and said stile, substantially as described.

FRANK MESKER.

THOMAS O. ARBEGUST.
